UNITED STATES PATENT OFFICE.

WILLIAM BUTTERFIELD, OF AUBURN, NEW YORK, ASSIGNOR TO D. M. OSBORNE & COMPANY, OF SAME PLACE.

CORD-TYING MECHANISM FOR GRAIN-BINDERS.

SPECIFICATION forming part of Letters Patent No. 365,044, dated June 21, 1887.

Original application filed May 26, 1884, Serial No. 132,815. Divided and this application filed October 22, 1885. Serial No. 180,659.
(No model.)

To all whom it may concern:

Be it known that I, WILLIAM BUTTERFIELD, of Auburn, in the county of Cayuga and State of New York, have invented certain Improvements in Cord-Tying Mechanisms for Grain-Binders, of which the following is a specification.

This invention relates to that class of machines which contain a rotary tying-bill consisting of a spindle with two jaws extending at substantially right angles to its axis.

The object of this invention is mainly to provide for the more certain engagement of the tying-bill with the cord at the commencement of the tying operation, and for the discharge of the knot from the tyer at the completion of the operation; and to this end it consists, generally speaking, in combining with the tying-bill operating mechanism whereby it is presented in a forward direction to receive the cord, revolved a part of one rotation to complete the knot, arrested with its bill in a backward position to permit the discharge of the knot, and, finally, turned to its original position, the entire operation of forming and discharging the knot being performed during a single rotation of the tyer.

For the purpose of illustration, I have represented my invention as embodied in a binding-machine of the well-known Appleby type, in which the binding arm or needle ascending through the binding-table, across the grain-passage, and through a slotted breast-plate presents the cord to a tying mechanism above the latter.

I have represented the invention embodied in connection with other details forming the subject of a separate patent, No. 333,922, dated January 5, 1886, and based on original application No. 132,815, of which the application for the present patent is a division; but it is to be understood that, with the exception of the means for imparting the intermittent rotation thereto, the entire tying mechanism may be of any ordinary construction.

Referring to the accompanying drawings, Figure 1 represents an outline elevation of the principal parts of the binding-machine. Fig. 2 is an elevation of the tying mechanism, com-

prising the cutting, clamping, and knotting devices. Fig. 3 represents a horizontal section taken immediately above the breast-plate. Fig. 4 is a side elevation of the tying-bill, its actuating-wheel, and other adjacent parts. Fig. 5 is a side elevation of the tying-bill and its actuating-wheel, the latter being shown in vertical section. Fig. 6 is a top plan view of the tyer-operating pinion.

Referring to the drawings, B represents the inclined binding-table, on which the loose grain is delivered in a continuous stream; C, the breast-plate overlying the table at a distance therefrom to confine the grain on the upper side; D, the compressor-arm, which rises above the table to confine the grain during the binding operation, and which subsequently descends to permit the discharge of the bound bundle.

E represents the rotary arm by which the bundle is delivered from the lower edge of the table; F, the tying-bill located above the breast-plate; G, the actuating-pinion secured to its spindle, and H the main driving-wheel, provided with teeth and delay-surfaces to impart an intermittent rotation to the tyer.

Except as to the peculiarities hereinafter detailed, the foregoing parts are of ordinary construction.

The tying-bill consists, as usual, of a spindle provided at one end with two laterally-extending jaws, one of which is fixed, while the other is pivoted, in order that it may be opened and closed for the purpose of grasping the end of the cord and drawing the same through a surrounding loop to complete the knot. The movable jaw *q* is held in a normally-closed position by means of a sliding rod, *r*, lying in a longitudinal groove in the spindle and acted upon at its upper end by a spring, *s*. The opening of this jaw during the proper portion of its revolution is effected by means of a stationary cam, *s*², which acts upon a roller attached to a heel projection of the movable jaw.

Heretofore it has been the custom to impart to the tyer a single continuous rotation, the jaws stopping always in one and the same position. In practice it is found that if this po-

sition be such as to insure the proper engagement of the cord with the tyer it will in most forms of machine prevent the convenient discharge of the knot. To avoid this trouble, I 5 provide the operating-wheel and the tyer-pinion with co-operating teeth and delay-surfaces of such character that during the rotation of the driving-wheel H the tyer is first held with its jaws in a forward position to receive the cord, then given about three-fourths 10 of a revolution in a forward direction, so as to form a loop and grasp the end of the cord, and stopped with its bill pointing in a rearward direction until the stripping of the knot 15 is effected, after which the forward rotation is continued until the bill resumes its original position ready to receive the cord for the next bundle. The tyer-pinion has teeth on one side only, while the opposite side has a flat delay-surface, l' , and a shoulder, m' . The wheel H is provided with teeth n' , to give a forward rotation to the pinion; also with an annular rim or delay-surface, o' , to co-operate with the surface l' and prevent the rotation of the tyer. The 20 wheel is further provided with an annular surface, p' , to encounter the shoulder m' on the pinion, and prevent the tyer from being turned too far ahead by reason of the impetus which it receives from the driving-gear. It 25 will be observed that the surfaces o' and p' extend but partly around the wheel, and that the gear-teeth are located between the ends of these surfaces. The tyer stands normally in the position shown by full lines in Fig. 3, being 30 held by the delay-surfaces o' acting against the surface l' of the pinion. As the wheel revolves, the delay-surface o' leaves the surface l' , and the teeth n' engage the pinion, imparting thereto and to the tyer about 35 two-thirds or three-fourths of a revolution, causing the tyer to twist the ends of the cord together in the form of a loop thereon. When the tyer reaches the position shown by dotted lines in Fig. 11, with the bill extending in a 40 rearward direction—that is to say, toward the delivery side of the machine—the teeth n' leave the pinion and the motion of the tyer ceases for the moment, its further rotation being prevented by the strain of the cord passing thence 45 to the sheaf. While the parts are in this position the rotary ejector-arm E acts upon the bundle, urging the same from the lower edge of the table, drawing or stripping the loop from the bill, which pulls the end of the cord 50 through the loop, thereby completing the knot. The forward end of the delay-surface o' of the wheel now acts against the delay-surface l' of the pinion, completing its rotation, so that both the pinion and the tyer assume their original 55 and normal positions. The reverse rotation of the tyer between the action of the driving-teeth and the action of the delay-surfaces is prevented by the roller on the heel of the tyer bearing with a spring pressure against the 60 abrupt face or shoulder of the stationary opening cam s^2 , before alluded to.

As regards the operation of the tyer, the es-

sence of the invention consists in giving the same but a partial rotation at a time, and causing its bill to be presented in one direction to receive the cord and in another direction to discharge the knot. 70

The skilled mechanic will understand that the details may be variously modified, and that many mechanical equivalents and devices 75 known in the art are applicable for the purpose of actuating the tyer.

As an additional means for insuring the proper delivery of the cord to and from the tying devices, I propose to make use of a 80 breast-plate having an angular slot therein, such as represented in Fig. 3. On reference to this figure it will be seen that the slot is deflected toward the tyer-spindle as it approaches the latter, and that it presents on the side distant from the spindle an oblique edge, b' , against which the cord rides in its passage to the tyer. When the tying-bill is in its normal or forward position, it extends obliquely across the slot and overlies the edge b' , as shown, 85 completely spanning or bridging the slot, so that the movement of the cord past the bill is impossible. In rear of the bill the slot extends laterally and obliquely therefrom toward the delivery side of the machine, presenting 90 an edge, c^3 . This edge lies in a plane nearly parallel with the direction of the bill. When the latter is in its backward position and the cord is forcibly drawn backward by the delivery of the bundle, the edge c^3 acts to crowd 95 or force the cord toward the extremity of the bill; or, in other words, it acts as a clearer or stripper to facilitate the discharge of the knot.

In order to prevent the edge b' from cutting or chafing the cord, I prefer to make use of a 100 breast-plate, g' , bolted to the outer side of the breast-plate, its edge being rounder and presented in position to form one side or edge of the slot, as plainly shown in Fig. 3.

I am aware that in a grain-binding machine 110 having a tyer of a form which requires one and one-half revolution to form the knot the tyer was presented with its bill in a forward direction to receive the cord and in a backward direction to discharge the knot; but I believe 115 myself to be the first to provide an organization under which each knot is completed and discharged by a single revolution of the tyer, and in which the tyer is presented in one position to receive the cord and in a different 120 position to permit the discharge of the knot.

Having thus described my invention, what I claim is—

1. The rotary tying-bill having the movable jaw to grasp the cord, in combination with means, substantially as described, for opening and closing said jaw, and with driving-gear whereby the tyer is given a single rotation and an interval of rest during the tying of each bundle, substantially as described and shown. 125

2. The tying-bill having the movable jaw, the spring acting to close the jaw, the stationary cam acting to open the jaw at each revolution of the tyer, the tyer-pinion provided with 130

teeth and delay-surfaces, and the driving-wheel provided with corresponding teeth and delay-surfaces, adapted, as described, to present the bill in one position to receive the cord, 5 subsequently impart thereto a forward rotation to complete the knot, then arrest the motion that the knot may be discharged, and finally continue the motion until the bill resumes its original position, whereby the formation and discharge of the knot are secured by a single rotation of the tyer.

3. In combination with the breast-plate having the slot curved toward the tyer in advance thereof and from the tyer in rear thereof, 15 the rotary tyer, and operating mechanism, substantially as described, whereby the tyer is first presented with its bill in a forward direction to receive the cord, then rotated a part of one revolution to form the knot, and stopped

with its bill in a backward direction to discharge the knot, and finally turned in the original direction to the starting-point. 20

4. The rotary tying-bill provided with the pinion, in combination with an actuating-wheel, said pinion and wheel constructed, as 25 described, to impart to the tyer an intermittent rotation with two stoppages during each rotation, one with the bill in a forward direction to receive the cord and the other with the bill in a rearward position to permit the discharge 30 of the knot.

In testimony whereof I hereunto set my hand, this 17th day of October, 1835, in the presence of two attesting witnesses.

WILLIAM BUTTERFIELD.
